FRANK J. JESCHKE, OF DETROIT, MICHIGAN, ASSIGNOR OF ONE-HALF TO JAMES J. YOUNG, OF DETROIT, MICHIGAN

GRINDING MECHANISM

Application filed February 5, 1931. Serial No. 513,494.

My invention relates to an improved grinding tool. It is here shown as embodied in a grinding device particularly adapted for re-boring worn cylinders or for finishing the bore in a cylinder.

An object is the provision of a grinding tool of the character described so constructed that the grinding elements or abrasives may be quickly and easily adjusted to an increased diameter to take care of wear and to perform the desired grinding operation. The construction is such that mechanism is provided to adjustably vary the grinding diameter established by the grinding elements during the grinding operation and as theretofore determined.

A feature of importance is the provision of means operable to automatically exert a force during the grinding operation to feed the abrasive elements outwardly to an increased diameter according to a predetermined desired setting and which means is preferably responsive to the initial impulse of rotation of grinding to be set or tensioned to produce this adjustable variation of the grinding elements during the grinding operation.

The adjustable mechanism is of such a character that the extent of outward movement of the grinding elements may be determined and set and then upon the initial impulse of rotation the adjustment mechanism is tensioned to feed the grinding elements outwardly according to this predetermined setting.

My invention is also characterized by the provision of grinding elements supported upon a tool body for outward radial adjustment, which body carries rotatable gear rollers extending lengthwise thereof and coupled with studs engaging the abrasives to radially adjust the abrasives upon rotation of the gear rollers. An adjustable gear collar surmounts the body and engages the rollers to actuate them upon its rotation.

Other important features and characteristics of my invention will more fully appear from the following specification, appended claims and accompanying drawings, wherein:

Fig. 1 is a side elevation of a preferred embodiment of my invention.

Fig. 2 is a vertical sectional view through an embodiment of my invention.

Fig. 3 is a horizontal sectional view taken on the line 3—3 of Fig. 2.

Fig. 4 is a horizontal sectional view taken on the line 4—4 of Fig. 2.

Fig. 5 is a vertical sectional view taken on the line 5—5 of Fig. 2, and

Fig. 6 is a fragmentary sectional view through a modified form of my invention.

In the drawings, let 10 indicate the driven spindle of a power machine which is coupled with a grinding tool through a universal joint formed by interfitting bearing elements 12 and 14, connected with a spindle by the pin 16. The element 14 is coupled with a driving collar 18 by screw studs 20, the inner reduced ends of which are seated in angular grooves 22 forming a bayonet joint effect which permits ready interlocking of the tool with the spindle.

The tool body 24 carries the abrasive or grinding elements 26 to rotate therewith and in such a manner as to permit the radial adjustment thereof to vary the grinding diameter. Three of these grinding elements are here shown, each including an abrasive stone mounted in a suitable channel back support. The back support of each stone is provided with a pair of studs 28 which extend through transverse openings formed in the body 24. These studs are notched as at 30 to be engaged by gear rollers 32 that extend lengthwise through the body and are rotatably supported therein so that rotation of the rollers advances or withdraws the studs to carry the abrasives.

Three of the abrasive elements are shown in the illustrative embodiment and three of the rollers are shown as extending lengthwise through the body and the body itself is shown as being of a hexagonal shape. The body is formed at its upper end with a shoulder and at this shoulder the rollers project beyond the diameter of the body for engagement with the gear teeth 34 of an adjustable gear collar 36 which surmounts the body so that rotation of the collar causes rotation of the rollers and movement of the abrasives. A plate 38 is secured by a screw stud 41 to the

bottom of the body to hold the parts in place.

The collar 36 has a cored out portion 40 within which is seated a coil spring 42, the lower end 44 of which is seated within a socket formed in the collar and the upper end 46 of which is seated within a socket formed in the driving collar or driving part 18, as shown in Fig. 2. The tool body has a reduced end portion 48 which extends upwardly through the adjustable gear collar 36 and through and into the driving collar 18, and a plate 50 is seated within the driving collar 18 and is attached by a screw stud 52 to the tool body to hold the driving collar to the body.

This upper extension 48 of the body is provided with a plurality of sockets 54 which are shown in Fig. 3 and which cooperate with a driving stud 56 that is threaded through a housing 58 carried by a ring 60 which encircles the driving collar. A driving collar 18 is cut away at its lower end as shown in Figs. 3 and 5 and as indicated at 62 so that while the driving collar drives the tool body through engagement of a face 62 with the housing 58 through which the screw stud 56 extends, when such stud is engaged in one of the recesses 54, it permits overrunning rotation and a lost motion rotation of the driving collar with respect to the body as determined by the extent of the cutaway portion of the collar and the position of the driving stud 56 in one of the apertures 54.

This permitted extent of lost motion or overrunning rotation is utilized to tension the spring 42 which in turn tensions the adjustable collar 36 to feed the abrasive elements outwardly during the grinding operation as now set forth.

In the operation of the device the adjustable collar may be rotated to bring the abrasives up normally to a diameter approaching the diameter of the cylinder bore to be ground and upon the first impulse of power rotation imparted through the spindle 10 there is a normal tendency for the abrasives to move outwardly into frictional engagement with the cylinder wall. The setting of the driving screw 56 will be such that a permitted motion of rotation is provided for. Upon frictional engagement of the abrasives with the cylinder wall the rotation of the tool body is resisted and the driving collar 18 overruns the body until a face 62 engages the housing 58 of the screw 56 and during this overrunning movement the spring 42 is tensioned which places a force upon the adjustable collar 36 tending to rotate it to feed the abrasives outwardly and which tension of the spring is utilized to feed the abrasives outwardly during the grinding operation and as wear occurs. It will therefore appear that with this tool the device may be so set as to provide for a determined feeding of the abrasives radially during the grinding operation and that

this is then accomplished automatically during the grinding operation by the functioning of the mechanism itself and without any further attention on the part of the operator.

In the construction shown in Fig. 6 an adjustment is also provided which is of a somewhat similar character but which is not automatic in its setting but is automatic in its functioning. In this case the construction of the tool body is similar to that heretofore described but the adjustable gear collar indicated as 136 and coupled by the spring 142 with the driving collar 118 is tensioned by manipulation of the collar 118 about the periphery of the upper extension 148 of the tool body. This rotatable adjustment of the part 118 is determined by corrugations 150 which seat an adjustment pin 152 held inwardly by a spring 154. The tension spring 142 may therefore be tensioned as desired to exert the desired thrust upon the gear collar 136 and during the grinding operation this thrust tends to feed the abrasives outwardly as heretofore described.

What I claim:

1. A grinding tool having, in combination, a body, abrasives carried thereby to rotate therewith and radially adjustable with respect to the body, a driving part coupled with the body through a lost motion connection to drive the body directly upon the taking up of said lost motion, adjustment mechanism including a rotatable member coupled with the abrasives to adjust their grinding diameter upon rotation of the member and a yieldable element coupling the member with the driving part to be tensioned during the lost motion movement of said part in picking up the body for rotation to urge said member rotatably.

2. A tool of the character described comprising, in combination, a body, grinding elements carried by the body and movable radially to adjusted positions, a driving part coupled with the body through a lost motion connection to rotate the body, adjustment mechanism coupled with said abrasives to actuate them radially and including an adjustable collar arranged intermediate the driving part and the body and means responsive to the lost motion rotation of the driving part relative to the body to place a tension on said adjustment collar tending to urge said abrasives outwardly.

3. A grinding tool having, in combination, a body, a plurality of abrasives carried thereby, a plurality of gear elements rotatably supported therein and coupled with said abrasives to vary the radial position thereof with respect to the body, an adjustable member coupled with said gear elements, a driving part coupled with the body and a yieldable element coupling said driving part with the adjustable member to place a tension thereon upon relative rotation of the driving part with respect to the body.

4. A grinding tool having, in combination,
a body, a plurality of abrasives extending
lengthwise thereof and rotatable therewith
and adjustable radially with respect thereto,
5 a plurality of gear elements extending length-
wise through the body and rotatable therein
and coupled with said abrasives to adjust
their radial position with respect to the body,
a rotatable collar coupled with said gear ele-
ments to rotate the same, a driving part
10 coupled with the body to rotate the body, a
spring coupling said driving part with the
collar to permit relative movement of the
driving part with the collar to place a tension
15 on the collar tending to urge said abrasives
outwardly to increase their grinding diam-
eter.

In testimony whereof, I, FRANK J.
JESCHKE, sign this specification.
